Primary Examiner — Marianne Pandozzi(74) *Attorney, Agent, or Firm* — Carlson, Gaskey & Olds, P.C.(57) **CLAIM**

The ornamental design for a mug, as shown and described.

DESCRIPTION

FIG. 1 is a perspective view of a mug in accordance with the present invention.

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded perspective view thereof.

The broken line depict portions of the mug that forms no part of the claimed design.

1 Claim, 7 Drawing Sheets(56)
